John Williams

UNITED STATES PATENT OFFICE.

JOHN WILLIAMS, OF DUNKIRK, NEW YORK.

ARRANGEMENT OF EXHAUST-PIPES IN LOCOMOTIVE-ENGINES.

Specification of Letters Patent No. 12,495, dated March 6, 1855.

To all whom it may concern:

Be it known that I, JOHN WILLIAMS, of Dunkirk, in the county of Chautauqua and State of New York, have invented a new and useful Improvement in Locomotives, called "Williams' Steam-Generator and Fuel-Saver"; and I do hereby declare that the following is a full, clear, and exact description of the same, reference being made 10 to the accompanying drawings, making a part of this specification.

The nature of my invention consists in creating a draft through the lower flues of the boiler by the interposition of a curtain, 15 consisting of two cylinders surrounding the escape or exhaust pipes and wings b , b , placed in the smoke arch by which the draft is directed more perfectly through these flues, and thus a fire or flue draft produced 20 in them; I also by my improvement am enabled to enlarge the escape or exhaust pipes one third more than as at present used in locomotives 25 and thus reduce the resistance upon the escape side of the piston; this is important in the rapid motion of a locomotive, where the pressure of the steam in the blast pipes is almost continuous. By my improvement 30 I furthermore save a third of the fuel at present used in locomotives, by directing the draft as above stated by which they are equally heated with the upper set of flues and being kept clear of soot and ashes the 35 desirable result of economy in the use of fuel is obtained.

The machine is constructed of sheet iron as follows; first a cylinder a , a , the front 30 part or that toward the head light of the engine resting on the bottom part of the smoke arch-reaching in height two or three inches above the top row of flues in the boiler; the back part of cylinder a , a or that 35 facing the fires is removed or left open at the bottom as shown in the drawing Fig. 3. The lower edge of a , is turned forming a bell mouth, while in the upper part holes of an inch diameter are made varying in 40 number according to the size of the locomotive. 2d, on the right and left sides of the cylinder and sustaining it are wings or cur-

tains b , b extending to the sides of the smoke arch, and in height varying according to the size of locomotive. 3d, in the inside of 45 aforesaid oval cylinder a , a , is placed a smaller one d , d , also oval and slightly conical affixed to the outer cylinder by braces, as shown in the drawing. These cylinders thus constructed and connected are placed 50 in the center of the smoke arch and around the exhaust pipes e , e as shown in drawing.

By my improvement I am enabled to enlarge the ends of the exhaust pipes one third 55 more than as at present used in locomotives and thus reduce the resistance upon the escape side of the piston; this is important 60 in the rapid motion of a locomotive, where the pressure of the steam in the blast pipes is almost continuous. By my improvement 65 I furthermore save a third of the fuel at present used in locomotives, by directing the draft as above stated by which they are 70 equally heated with the upper set of flues and being kept clear of soot and ashes the 75 desirable result of economy in the use of fuel is obtained.

Having described my improvement, what I claim as my invention and desire to secure by Letters Patent, is—

Surrounding the exhaust pipes e , e , with cylinders a ,—and d , the outer one connected by wings b , b , with the sides of the smoke arch, for the purposes of economizing fuel, and power of the engine as well as equalizing 75 the draft through the lower flues of the boiler, substantially as set forth.

In testimony whereof I have signed my name before two subscribing witnesses.

JOHN WILLIAMS.
